UNITED STATES PATENT OFFICE.

FRIEDRICH WOHLMANN, OF LOS ANGELES, CALIFORNIA.

EXTENSION-TABLE.

1,351,457.

Specification of Letters Patent. Patented Aug. 31, 1920.

Application filed October 26, 1916, Serial No. 127,936. Renewed June 9, 1920. Serial No. 387,722.

To all whom it may concern:

Be it known that I, FRIEDRICH WOHLMANN, a subject of the Emperor of Germany, residing in the city and county of Los Angeles, State of California, have invented certain new and useful Improvements in Extension-Tables, of which the following is a specification.

My invention relates to an extension table 10 of the type in which one or more leaves are housed beneath the top of the table and arranged to be drawn from their housed position and moved into a position to form a continuation of the top.

15 The primary object of the invention is to provide a simple form of extension table including a fixed top portion and supplemental top portions or leaves which can be easily and quickly moved to and from their 20 housed position with a straight push or pull requiring merely a minimum effort and which leaves can be held automatically braced in extended position simply by moving the same into extended position and 25 without the necessity of actuating any holding means.

Various other objects and advantages of the invention will be in part obvious from an inspection of the accompanying drawings 30 and in part will be more fully set forth in the following particular description of one form of mechanism embodying my invention, and the invention also consists in certain new and novel features of construction 35 and combination of parts hereinafter set forth and claimed.

In the accompanying drawings:

Figure 1 is a longitudinal sectional view showing a preferred embodiment of my invention with the leaves and carriages in 40 housed position and taken on the line 1-1 of Fig. 3 looking in the direction indicated by the arrows;

Fig. 2 is an enlarged view of the left side 45 of the device shown in Fig. 1 with one of the carriages and its leaf in extended position;

Fig. 3 is a transverse sectional view taken on the line 3-3 of Fig. 1; and

Fig. 4 is a view showing the underside of 50 the table with one of the leaves in engagement with the table top.

In the drawings, there is shown what may be regarded as a conventional form of table formed of a rectangular frame supported on 55 legs 5 and including side sills 6, end sills 7 and a top 8 fixed thereto as is usual with de-

vices of this character. Extending transversely across the underside of the top and fixed centrally thereto is a stop strip 9. The form of the device illustrated includes two 60 leaf-supporting carriages, designed to be extended longitudinally from the opposite sides of this stop strip, but as these devices are similar in construction and operation the detailed description of either one will 65 be sufficient for the other.

The side sills are connected below each of the outer edges of the stop strip by a carriage-supporting-member 10 in the form of a board disposed vertically, the upper side 70 of which is cut to provide a pair of step portions 11 and 12 (see Fig. 3), designed to support respectively the carriages 13 and 14 when in housed position as shown in Fig. 1. The carriages are similar in construction and 75 each includes a pair of longitudinally extending runners 15 and 16, connected by a pair of longitudinally spaced and transversely extending struts 17 in the form of flat pieces fixed to the runners adjacent their 80 upper edges as shown more particularly in Fig. 2. This arrangement of transverse struts permits one of the carriages to telescope within the other as shown in Fig. 3, incidentally providing a construction which 85 offers the minimum obstacle to the positioning of drawers within the table or otherwise utilizing the open space beneath the table top. The top of the runners have a straight edge 18 designed to engage the underside of 90 the top over a material area so as to brace the cantilever construction formed by the carriage when in extended position. The inner end of each of the runners is inclined as shown at 19 and provided with a shoulder 95 notch 20 adapted to engage and underlap the stop strip 9 when the carriage is in extended position to thus prevent the carriage from accidentally sliding inward when the leaf hereinafter described is moved into engagement with the fixed top.

Opposite sides of each of the transverse sills are recessed to provide runways 21 for the runners. The underside of the runners are designed so that when drawn across the 105 runway 21 the carriage will be moved vertically so as to bring the leaf 22, supported thereby, up onto a level with the top 8. For this purpose the underside of the runners are each provided with an angled incline 23 110 arranged so that when the runner has moved into housed position a distance sufficient to

permit the leaf to clear the top 8, the incline 23 comes into engagement with the runway 21 and a further continued movement of the runners of the carriage across the runway 5 causes the same to be elevated to bring the leaf on a level with the fixed table top, (see Fig. 2). The incline 23 terminates in a stop 24 adapted to engage against the inside of the end sill to limit any further outside movement of the carriage. The leaf 22 is slidably mounted upon the carriage and is guided for movement to and from the top. The leaf is fastened to the carriage and held against vertical movement relative thereto by means of L-irons 25 fastened to the underside of the leaf and having a projecting flange slidably mounted in grooves 26 on the inner faces of the runner, as shown more particularly in Fig. 3. The 10 runners are also provided with beveled edge stops 27 so positioned that when the leaf is in abutting engagement with the top, one of the angle irons 25 will have passed over the stops thereby locking the leaf in engagement with the top.

In operation, and assuming that the carriages and leaves are in the housed positions shown in Fig. 1 either one or both of the carriages may be drawn from their housed 15 positions lengthwise of the table simply by pulling on the leaf to be used. This action will cause the carriage with the leaf depressed below the level of the top to be moved outwardly from the frame and when approaching the end of its run the incline 23 will cause the carriage to elevate the leaf until it is level with the top in which position the inner end of the withdrawn carriage will be in engagement with the stop 20 strip. The extended leaf is then pushed back into engagement with the top, the angle irons passing over the clips to lock the leaves into position.

In order to telescope the carriage and its 25 leaves into housed position beneath the fixed top, the leaf to be housed is raised slightly so that the angle irons will clear the stops and the leaf is then drawn out into the position shown in Fig. 2, a distance sufficient to clear the top. In this 30 position the iron 25 is disposed in the recess 28 thus holding the leaf to the carriage and permitting the carriage to be moved back into telescoped position when pressure is applied to the outer edge of the leaf. At this 35 time the outer end of the carriage is lifted slightly so that the inner end will clear the stop piece and then the carriage and its leaf is moved back into the position shown in Fig. 1 and the table is then in its original 40 normal position and in this position resembles the conventional form of table now in general use.

By means of a device of this character 45 there is attained an ease of operation, the

frictional contact between parts having been reduced to a minimum. In either collapsed or extended position, the parts are firmly braced against any tilting movement. One of the elements of the device disclosed is 70 simplicity of parts and ease of operation. The device may readily be installed in any conventional form of table, merely by properly recessing the end sills and mounting the carriage and its leaves in position on 75 such modified conventional form of table. The appearance of the table is preserved, it being possible by means of the construction illustrated, to use the leaves of the same width as the stationary top and the 80 depths of the structural parts is but slightly increased to accommodate the housed extensions.

Having thus described my invention, I 85 claim:

1. In an extension table, a frame provided with supporting legs and including a fixed top, a stop strip fixed to the underside of said fixed top and a transverse member recessed to provide a runway, a carriage slidably mounted in said runway movable to and from a position stored beneath the fixed top, and provided with an inclined underside designed to elevate the carriage when drawn along said runway from its stored 95 position and a leaf slidably mounted on said carriage and arranged when the carriage is extended to be moved horizontally into engagement flush with the top surface of said fixed top, said carriage provided with means for engaging said stop strip to hold the same while the leaf is being moved into engagement with the fixed top.

2. In an extension table, a frame provided with supporting legs and including a fixed top, a stop strip fixed to the underside of said fixed top and a pair of transverse members each designed to constitute a carriage support, a pair of carriages each provided with a sliding leaf mounted thereon and each movable to and from a position stored beneath the fixed top, said carriages being movable across said supports, and each provided with an inclined underside for engaging the supports to elevate the 110 carriages when the leaves carried thereby have cleared the fixed top, said carriages including longitudinal members with the members of one carriage telescoping within the members of the other carriages when in 115 stored position and the telescoped carriage being slightly depressed to provide clearance for the other carriage.

3. In an extension table, a frame provided with supporting legs and including a fixed 120 top, of a leaf supporting carriage slidably mounted in the frame and movable to and from a position stored beneath the fixed top, a leaf slidably mounted on said carriage and fixed thereto against vertical movement,

said carriage provided with guiding means for causing said leaf to remain depressed below the fixed top until it has cleared said top when drawn from its stored position 5 and said guiding means including an incline for elevating the leaf to the level of said fixed top.

4. In an extension table, a frame provided with supporting legs and including a fixed 10 top, of a leaf supporting carriage slidably mounted in the frame and movable to and from a position stored beneath the fixed top, a leaf slidably mounted on said carriage and fixed thereto against vertical movement, 15 said carriage provided with guiding means for causing said leaf to remain depressed below the fixed top until it has cleared said top when drawn from its stored position and then elevated to the level of said fixed 20 top and means for holding said carriage while permitting independent sliding movement of the leaf horizontally into engagement with the fixed top.

5. In an extension table, the combination 25 with a frame including a fixed top and a stop strip, of a carriage slidably mounted in said frame and adapted when in extended position to abut against said strip, a leaf slidably mounted on said carriage and 30 means for elevating the carriage to bring the leaf offset from and level with said fixed top, said leaf being slidable on the carriage in a direction toward the stop strip and into engagement with the fixed top, said stop strip acting to prevent accidental collapsing 35 of the carriage when the leaf is moved into engagement with the fixed top.

6. In an extension table, the combination

with a frame including a fixed top, of a carriage slidably mounted in said frame, a leaf 40 slidably mounted on said carriage, guiding means for causing said carriage to remain depressed below the fixed top until it has cleared said top when drawn from its stored position and for then elevating the carriage 45 to bring the leaf offset from and level with said fixed top, said leaf being slidable on the carriage into engagement with the fixed top and means for holding the inner end of the carriage locked in elevated position. 50

7. In an extension table, the combination with a frame including a fixed top, of a carriage slidably mounted in said frame and adapted to be telescoped into the frame, said carriage having a leaf guideway, a leaf 55 slidably mounted in said guideway, the underside of said carriage provided with an incline so positioned as to cause the carriage to move vertically after it has cleared said top as it is moved from the frame. 60

8. In an extension table, the combination with a frame including a fixed top, of a carriage slidably mounted in said frame and adapted to be telescoped into the frame, said carriage having a leaf guideway, a leaf 65 slidably mounted in said guideway to and from the fixed top, the underside of said carriage provided with an incline causing the carriage to move vertically as it is moved from and into the frame, and means for bracing 70 the carriage from the frame when in extended position drawn from the frame.

Signed at New York city in the county of New York and State of New York this twenty-fourth day of October, A. D. 1916. 75

FRIEDRICH WOHLMANN.
